Patented Dec. 3, 1974

233,855

IDENTIFICATION PHOTOGRAPHY JIG

Ronald E. Mertens and Frank W. Davis, Indianapolis,
Ind., assignors to Photo Communications, Inc., Indian-
apolis, Ind.

Filed Apr. 25, 1973, Ser. No. 354,233

Term of patent 14 years

Int. Cl. D16—99

U.S. Cl. D61—1 E

FIG. 1

FIG. 2

FIG. 3

FIG. 4

FIG. 5

FIG. 1 is a top plan view of an identification photography jig showing our new design;

FIG. 2 is a left side elevational view thereof, the right side being a mirror image thereto;

FIG. 3 is a bottom plan view thereof;

FIG. 4 is a front elevational view thereof; and

FIG. 5 is a rear elevational view thereof.

We claim:

The ornamental design for an identification photography jig, as shown and described.
